UNITED STATES PATENT OFFICE.

BENJAMIN LEV, OF CLEVELAND, OHIO, ASSIGNOR TO ECLIPSE RAILWAY SUPPLY CO., OF KANSAS CITY, MISSOURI, A CORPORATION OF DELAWARE.

TRIPPING MEMBER FOR CAR-FENDERS.

No. 815,106.

Specification of Letters Patent.

Patented March 13, 1906.

Application filed July 15, 1904. Serial No. 216,728.

To all whom it may concern:

Be it known that I, BENJAMIN LEV, a citizen of the United States, residing at Cleveland, in the county of Cuyahoga and State of Ohio, have invented certain new and useful improvements in Tripping Members for Car-Fenders; and I do declare that the following is a full, clear, and exact description of the invention, which will enable others skilled in the art to which it appertains to make and use the same.

My invention relates to tripping members for car-fenders; and the invention consists in the construction and arrangement of parts, substantially as shown and described, and particularly pointed out in the claims.

In the accompanying drawings, Figure 1 is a perspective view of the front portion of a car and my improved fender mechanism thereon. Fig. 2 is a plan view of the carrier-frame with the cushioning member thereon, and Fig. 3 is a perspective view of one corner of said frame as hereinafter fully set forth.

The idea of this invention is to provide a new construction and arrangement of tripping or cushioning member for the fender or fender-carrier which is flexible and adapted to yield by stretching at some point provided for that purpose or throughout its length when it strikes an object, and means to take up slack and to keep the same stretched, as hereinafter fully set forth.

As shown, A represents the car; B, the supporting-frame, carried at the front of the car and adapted to fold as usual; C, the carrier, and D the tripping member thereon. Suitable hangers H support the frame B, and there is a spring-buffer F at the rear, as usual.

The entire carrier is designated by C and comprises an outer frame c of rigid construction and in this instance provided with corner connections G at its front, having forward extensions g with keyhole-slots g' and fashioned in rocker form, so as to afford or provide striking-points for the front of the carrier in case the same is thrown down to the pavement or track. In that event these

rounded rocker-shaped bottom projections take the wear and support the fender at that point. Ordinarily, however, the carrier is 50 supposed to run at such elevation at its front as to bring the cushioning or striking member D to an elevation about or above the ankles, and for this reason there is not ordinarily any danger that the carrier will 55 touch the ground at its front.

The cushioning or tripping member D in any event is flexible if not elastic, and hence may be made of rubber or of woven, twisted, or other fibrous material and construction, 60 such as a rope or the like, and the ends thereof are connected by a spirally-wound spring d and a turnbuckle d', adapted to take up any slack in the said member and to keep it stretched as tightly as may be deemed necessary. 65

It will be observed that the bracket G is rounded in its forward portion at g², around which the part D is drawn and which serves to protect said part at that point, and rollers 70 might be interposed here, if thought best.

The keyhole g' is adapted to draw certain portions of the tripping member through the same, but not necessarily the spring d nor the turnbuckle d', and the ends of said member are 75 shown as both elastically and adjustably connected. By threading the part D through the extensions g from the outside the ends thereof are brought inside, where connections 80 can be made out of the way and the plain portion of the device kept at the front.

What I claim is—

1. In car-fenders, a fender-frame provided with forward extensions at its front corners and a flexible tripping member engaged in 85 said extensions and having its ends connected by a flexible portion.

2. In car-fenders, a fender-frame and a flexible tripping member threaded through the front ends of the same and having its ends 90 adjustably connected between the sides of the fender.

3. In car-fenders, a fender-frame having forward extensions at its front and corners,

in combination with a flexible tripping member threaded through holes in said extensions and having its ends adjustably and flexibly connected.

5 4. In car-fenders, a fender provided with downward extensions at its front constructed beneath to take up wear in striking ground and provided with holes, in combination

with an elastic tripping member threaded through said holes and free therein.

In testimony whereof I sign this specification in the presence of two witnesses.

BENJAMIN LEV.
